UNITED STATES PATENT OFFICE

DONALD B. MACNEIR, OF NEW YORK, N. Y.

RAILWAY TIE

Application filed September 28, 1929. Serial No. 395,918.

This invention relates to improvements in railway ties.

The primary object of the invention resides in means for yieldingly supporting railway rails upon concrete blocks in lieu of the usual wood ties, and for securely fastening the rails to the concrete blocks.

Another object of the invention is the provision of a rail tie in which a cushion block is interposed between the base of the rail and the top of the concrete block for allowing the rail to yield downward as the rolling stock passes thereover and to arrest any shock or strain which might tend to fracture the concrete block.

A further object is to provide a U-shaped member embedded in the concrete base or block, the legs of which extend above the top of the block and straddle the sides of the rail to receive clamping lugs which lock thereon and engage the flanges of the rail to maintain the same in position upon its cushioned seat.

With these and other objects in view, the invention resides in certain novel construction and combination and arrangement of parts, the essential features of which are hereinafter fully described, are particularly pointed out in the appended claims, and are illustrated in the accompanying drawings, in which:

Figure 1 is a vertical transverse sectional view through a road bed showing a pair of rails supported upon my improved ties.

Figure 2 is an enlarged vertical transverse sectional view through one of the rails and its support.

Figure 3 is a side elevational view thereof.

Figure 4 is an enlarged detail vertical sectional view through one of the rail clamping lugs and its correlated parts.

Figure 5 is a detail horizontal sectional view on the line 5-5 of Figure 4.

Referring more particularly to the drawings, the numerals 10 and 11 designate a pair of spaced opposed concrete blocks which are identical in construction so that a description of one will suffice for the other.

The side walls of each of the blocks taper upwardly so that the base of each block is

larger than the top thereof. Embedded in each of the concrete blocks 10 and 11 is a substantially U-shaped member 12, the legs 13 of which extend above the top face of the block and which legs are square in cross section for a purpose to be presently explained. The inner side faces of the legs 13 are provided with ratchet teeth 14, which ratchet teeth terminate short of the terminal ends of the legs, and which terminal ends at their upper portions are round in cross section as indicated at 15 and provided with heads 16.

Seated upon the top of each of the concrete blocks 10 and 11 is a cushion member or block 17, which may be made of wood, semi-hard rubber or zernathereum, or any other suitable yieldable substance. The cushion blocks 17 are disposed between the legs 13 of the respective U-shaped members and act as yieldable seats for the railway rails 18 of the usual well known construction. The inner and outer sides of the cushion blocks project beyond the base flanges of the rail and are recessed as at 19, as clearly shown in Figure 3 of the drawing and in dotted lines in Figure 2 thereof.

Slidably mounted on the legs 13 of the respective U-shaped members 12 are rail clamping lugs 20, each of which includes an inwardly extending lip 21 and a downwardly extending lug 22. The body of each clamping lug 20 is provided with a vertically disposed square opening 23, one wall of which is provided with a series of ratchet teeth 24 for coacting engagement with the series of ratchet teeth 14 provided on the respective legs 13. The square openings 23 in the clamping lugs 20 are slightly larger than the cross sectional area of the squared portion of the legs 13 to permit vertical sliding of the lugs relative to the legs to facilitate movement of the same to an adjusted position in clamping engagement with the base flanges of the rails 18. When the clamping lugs 20 are in clamping engagement with the base flanges of the rails 18, as shown in the drawings, the lugs 22 are received in the recesses 19 to permit the lip 21 and the lugs 22 to snugly engage the flange of the rail and the cushion member 17 to prevent shifting of one relative to the other.

Should it be desired to replace a rail 18, the legs 13 of the U-shaped member 12 are bent outwardly to allow the clamping lugs 20 to be raised to a plane level with the rounded portion 15 thereon whereupon the said clamping lugs may be given a one-quarter turn so that upon lifting of the rails, the same may clear the clamping lugs as will be readily appreciated.

For the purpose of bracing the two opposed concrete blocks 10 and 11, I provide the inner leg 13 of each of the U-shaped members 12 of the respective blocks 10 and 11 with a link 24, the outer end of which extends beyond the inner side of the block and is formed with an eye 25. The inner end of each link 24 is also provided with an eye 26 through which the leg 13 to which it is connected passes. By referring to Figure 1 of the drawings it will be noted that the eyes 25 of the links 24 embedded in the blocks 10 and 11 extend inwardly toward each other and are disposed in substantial alinement. Connected to the eyes 25 is a tie rod 27, the opposite ends of which terminate in eyes 28 which engage the eyes 25 to provide a loose connection between the opposed concrete blocks 10 and 11. The tie rod 27 acts to retain the opposed concrete blocks in position against inward or outward spreading but allows a limited amount of movement between the same which is necessary during the passage of rolling stock over the rails. From the foregoing description it will be understood that I have constructed a railway tie having the yielding qualities of the well known wood tie, but wherein concrete blocks act as the base thereof for embedment in the roadbed and which will be found to have longer life than the commonly used wood tie. By cushioning the rails upon the concrete block, any shock or vibration caused by rolling stock passing over the rails will be taken up, thus preventing the same from passing to the concrete block which otherwise might cause fracture thereof. It might also be mentioned that the interlocking ratchet teeth between the clamping lugs and the legs 13 of the U-shaped member 12 permit positive clamping of the rail to its cushion seat and due to the angularity of the teeth, the said clamping lugs may be easily adjusted to clamping position with engagement with the base flanges of the rail, but are prevented from any accidental upward movement or loosening which might be caused by the continued vibration caused by the rolling stock passing over the rails. The heads 16 hereinbefore mentioned serve to prevent separation of the clamping lugs from their respective legs 13.

While I have described what I deem to be the most desirable embodiment of my invention it is obvious that many of the details 65 may be varied without in any way depart-

ing from the spirit of the invention, and I therefore do not limit myself to the exact details of construction herein set forth, except as defined by the appended claims.

Having thus described the invention, what I claim as new and desire to secure by Letters Patent is:—

1. In a railway tie construction, a pair of spaced opposed concrete blocks, eyes extending from said concrete blocks and anchored therein, and a tie rod having its ends respectively connected to said eyes. 75

2. In a railway tie construction, the combination of a pair of opposed concrete blocks, U-shaped members embedded thereon, links connected to a leg of said U-shaped members and extending beyond said blocks, and a tie rod bridging the space between said blocks and having its opposite ends flexibly connected to said links. 80

3. In a railway tie construction the combination of a pair of opposed blocks, an upright member embedded in each of said blocks, a link connected to each of said upright members and also embedded in its respective block, each of said links extending beyond its block and being provided with an eye, and a tie rod bridging the space between said blocks and having its opposite ends also provided with eyes, an eye of said tie rod engaging the juxtaposed eye of the contiguous link. 95

In testimony whereof, I have affixed my signature.

DONALD B. MACNEIR.
